UNITED STATES PATENT OFFICE.

LOUIS DE K. HUBBARD, OF MIDDLETOWN, CONNECTICUT, ASSIGNOR TO
THE RUSSELL MANUFACTURING COMPANY, OF MIDDLETOWN, CON-
NECTICUT.

BANDOLEER OR BELT.

No. 836,580.

Specification of Letters Patent.

Patented Nov. 20, 1906.

Application filed January 30, 1905. Serial No. 243,306.

To all whom it may concern:

Be it known that I, LOUIS DE K. HUBBARD, a resident of Middletown, in the county of Middlesex and State of Connecticut, have invented certain new and useful Improvements 5 in Bandoleers or Belts; and I do hereby declare the following to be a full, clear, and exact description of the invention, such as will enable others skilled in the art to which it appertains to make and use the same.

My invention relates to an improved bandoleer or belt, the object of the invention being to provide a bandoleer or belt of woven fabric with integrally-woven longitudinal 15 pockets; and with this object in view the invention consists in certain novel features of construction and combinations and arrangements of parts as will be more fully herein-after described, and pointed out in the claims.

In the accompanying drawings, Figure 1 is a view in elevation, illustrating my improvements. Fig. 2 is a view in longitudinal section, and Fig. 3 is a view in section at right angles to Fig. 2.

1 represents the woven body of the bandoleer or belt, and 2 pockets extending longitudinally of the body and woven integral therewith. Above the open ends of the pockets flaps 3 are provided to close the open 25 end of the pockets, preventing entrance of snow and rain therein and excluding dust and dirt. The exact shape of the pockets is immaterial, and they may be made of various sizes, the essential features being that the pockets are integral with the body of the bandoleer or belt and are located longitudinally thereof.

Any form of end fastener may be employed

on the bandoleer or belt, and while the latter is especially designed for cartridges the pockets may contain any other articles or material and may be of a size and shape to suit the use to which it is to be put.

A great many slight changes might be made in the general form and arrangement 45 of the parts described without departing from my invention, and hence I do not restrict myself to the precise details set forth, but consider myself at liberty to make such slight changes and alterations as fairly fall 50 within the spirit and scope of my invention.

Having fully described my invention, what I claim as new, and desire to secure by Letters Patent, is—

1. An article of the character described, 55 consisting of a strip of woven fabric having pockets disposed longitudinally thereon, each of said pockets having its sides and bottom woven integral with the strip and having its top open and disposed at right angles to 60 the length of the strip.

2. A bandoleer or belt, comprising a woven strip or body having a series of pockets disposed longitudinally thereon, the bottom of each pocket woven integral with the woven 65 strip or body crosswise of the latter, and the sides of each pocket woven integral with the woven strip or body coincident with the longitudinal edges of the latter.

In testimony whereof I have signed this 70 specification in the presence of two subscribing witnesses.

LOUIS DE K. HUBBARD.
